UNITED STATES PATENT OFFICE.

EDWARD CARSON WALLER, OF CHICAGO, ILLINOIS, ASSIGNOR TO THE LUXFER PRISM PATENTS COMPANY, OF SAME PLACE.

DESIGN FOR A PRISM-PLATE AND BORDER.

SPECIFICATION forming part of Design No. 28,018, dated December 7, 1897.

Application filed October 13, 1897. Serial No. 655,086. Term of patent 14 years.

To all whom it may concern:

Be it known that I, EDWARD CARSON WALLER, a citizen of the United States, residing at Chicago, in the county of Cook and State of Illinois, have invented a certain new and original Design for Prism-Plates and Borders, of which the following is a description.

My invention relates to designs for prism-plates and borders and is illustrated in the accompanying drawings, wherein—

Figure 1 is a view of a prism-plate and border of my design. Fig. 2 is a cross-section therethrough on the line 2 2.

A is a prism-plate comprising a substantially-flat body with prisms C on one side

thereof. Surrounding the prism-plate is a border B, dished toward the prism side, as shown in the cross-section. I have shown the border as ornamented with open-work at D.

The essential feature of my design is found in a prism-plate with a surrounding border dished toward the prism side. 20

I claim—

The design for a prism-plate and border, substantially as shown and described.

EDWARD CARSON WALLER.
